UNITED STATES PATENT OFFICE

1,993,046

MERCURY SWITCH

Carl J. Warnke, Elkhart, Ind., assignor, by direct and mesne assignments, to The Adams & Westlake Company, Chicago, Ill., a corporation of Illinois

Application April 29, 1933, Serial No. 668,496

5 Claims. (Cl. 200—152)

This invention relates to mercury switches and particularly to the chemical composition of the constituent elements of the switches.

The principal object of the invention is to provide a switch which, because of the materials that are used and their relationship to each other, will long outlive the ordinary switch.

Of prime importance is the gas fill which I use in the switch envelope. I have found that certain gases have amazing dielectric properties and are far more inert and resistant to ionization than hydrogen, or any of the other gases commonly used in mercury switches.

For example, a hydrogen-filled switch made in accordance with approved manufacturing practice may have a maximum useful life of 4000 cycles of operation under given conditions of load, whereas a switch made in accordance with this invention, and operating under the same load, has been put through more than five million cycles of operation without any marked sign of deterioration. This remarkable demonstration of endurance shows clearly that a vastly improved switch has been made, and I believe that its superiority is largely due to the unusual properties of the gases which I use for fills.

In brief, I have discovered that certain gases are infinitely more suitable for gas fills in mercury switches than the gases now used; also I have found that these gases are employed to the best advantage when the other constituents of the switch are made of certain materials that do not react with each other, or with the gas fill of the switch.

In my Patent No. 1,967,952 issued July 24, 1934, I have disclosed a method and apparatus for producing gases having substantially greater resistance to ionization than hydrogen and being relatively incapable as compared with hydrogen of reacting with or being absorbed by such metals as platinum, tungsten, molybdenum, tantalum and vanadium. These gases, I believe to be hydrides of helium, neon, argon, silicon, and boron, and in the companion application, which is hereby made a part of the disclosure of this application, I have given evidence to substantiate my belief.

But whatever the chemical composition of these gases, it is a proven fact that they greatly lengthen the life of the switches and improve their operating characteristics.

These new and improved gases, which for convenience will be called "X" gases, have other interesting and useful properties. Because of their complete, or substantially complete inertness, they do not react with, nor are they absorbed by the

switch electrodes. As a consequence, the electrodes do not wear away or deteriorate with use.

In my United States Letters Patent No. 1,883,146, issued Oct. 18, 1932, I disclosed the fact that mercury switches filled with hydrogen which had been purified in a certain manner, had twice the life of ordinary switches. The "X" gases, when used in mercury switches, do infinitely more; they lengthen the useful life of the switches a thousand fold. Actual tests have proven this statement to be a fact.

The amazing action of the "X" gases is further demonstrated by tests that were made with four switches identical in all particulars except the gas fill. In switch No. 1, purified hydrogen was used; in switch No. 2, helium; in switch No. 3, a physical mixture of helium and hydrogen; and No. 4, one of the "X" gases (helium hydride). All switches were subjected to the same load, and it was observed that after a short time, switch No. 1 was warm; switch No. 2 was hot; switch No. 3 was warmer than switch No. 1, but not as hot as switch No. 2; and that switch No. 4 showed no signs whatsoever of being heated.

As the "X" gases are not absorbed by and do not react with the electrode materials, it follows that the surfaces of the electrodes are always clean and consequently a good contact is always assured. Furthermore, as a film cannot form on the surfaces of the electrodes in the presence of the "X" gases, the contact resistance of the switch does not increase with use.

Further and other objects and advantages will become apparent as the disclosure proceeds and the description is read in conjunction with the accompanying drawing, in which

Fig. 1 is a diagrammatic view showing the method which I employ for filling mercury switches with "X" gases; and

Fig. 2 is a longitudinal, sectional view showing one type of mercury switch to which this invention is applicable.

The mercury switch which has been shown is but one of many types, and is used for the purpose of disclosure only. Preferably, the glass envelope 10 is made of magnesium-silicate glass that is substantially free from lead, tin, antimony, and other substances which decompose under the action of an electric arc. Both other glasses such as boro-silicate glass may be used instead.

A pair of leads 11 and 12 are sealed through one end of the envelope and these leads may be of molybdenum, tungsten, or any other suitable material.

The inner ends of the lead-in conductors are equipped with electrodes 13 and 14 which may be of platinum, tungsten, molybdenum, tantalum, vanadium, or any other suitable material.

- 5 A quantity of mercury 15 is placed in the envelope prior to sealing and is adapted to make or break an electrical circuit through the electrodes according to the position of the switch. The mercury is purified prior to being introduced into the envelope to remove all traces of oxides, water vapor, carbo-hydrates, and other impurities which decompose under the action of the electric arc.

10 Before the switch envelope is sealed off as indicated at 16, it is exhausted and filled with one of the "X" gases, and I prefer to use the gas that is formed by passing helium and hydrogen through my apparatus as disclosed in my Patent No. 1,967,952 which constitutes a part of this disclosure.

15 The method which I use for exhausting the envelope and filling it with an "X" gas is shown in Fig. 1. The container 17 preferably contains a physical mixture of helium and hydrogen in the proportion of two volumes of helium to one volume of hydrogen. The top of the container is connected by a tube 18 with the apparatus 19 that converts the helium and hydrogen into what I believe is helium hydride. The outlet 20 of the apparatus is packed with cotton 21, or other filtering material acting merely to prevent the precipitated solids entrained in the purified gas from being carried into the switches.

20 A high vacuum pump 22 is provided for exhausting the switch envelope 10 and this is connected with the envelope by turning the stop cock 23 to a position in which the passages 24 and 25 communicate with the tube 26 leading to the vacuum pump 22, and the tubulation 27, connected by the rubber hose 28 to the top of the switch envelope, respectively. When the stop cock 23 is in this position, the switch envelope is closed to the apparatus 19.

25 After the envelope has been thoroughly exhausted (the envelope should be heated during evacuation to remove occluded gases), the stop cock 23 is turned to a position in which the passage 25 communicates with the outlet 20 of the apparatus 19 and the passage 24 communicates with the tubulation 27. A valve 29 in the outlet 20 regulates the flow of gas from the apparatus and the pressure in the envelope may be measured by the pressure gauge 30. As soon as the switch envelope is placed in communication with the apparatus, the gauge 30 immediately drops to approximately a zero reading and thereafter

slowly rises as gas is admitted through the valve 29 into the envelope. When the proper pressure has been reached, preferably about five inches less than atmospheric pressure, the stop cock 23 is turned to the position shown in Fig. 1 and the top of the switch envelope is then sealed off to complete the switch.

5 Under some conditions of use, inferior materials may be substituted for certain components of the switch in order to cut down the cost of manufacture, and it will be understood that this invention is not limited to the use of the preferred materials conjointly. But for best results, the preferred materials should be used.

10 What I claim, therefore, is:

1. In a mercury switch, a glass envelope, spaced electrodes in the envelope, a quantity of mercury in the envelope adapted to be manipulated to make or break an electrical circuit through the electrodes, and a gaseous hydride 15 of the inert gases in the envelope.

2. In a mercury switch, a glass envelope, spaced electrodes in the envelope, a quantity of mercury in the envelope adapted to be manipulated to make or break an electrical circuit 25 through the electrodes, and a gas fill of helium hydride.

3. In a mercury switch, a glass envelope, spaced electrodes in the envelope, a quantity of mercury in the envelope adapted to be manipulated to make or break an electrical circuit 30 through the electrodes, and an inert arc suppressing gas in the envelope formed by passing a mixture of helium and hydrogen through an electric arc in the presence of one or more ionized 35 hygroscopic metals.

4. In a mercury switch, a glass envelope, spaced electrodes in the envelope, a quantity of mercury in the envelope adapted to be manipulated to make or break an electrical circuit 40 through the electrodes, and an inert arc suppressing gas in the envelope formed by passing a mixture of helium and hydrogen through an electric arc in the presence of ionized titanium 45 and one or more strongly hygroscopic metals.

5. In a mercury switch, a glass envelope, spaced electrodes in the envelope, a quantity of mercury in the envelope adapted to be manipulated to make or break an electrical circuit 50 through the electrodes, and an inert arc suppressing gas in the envelope formed by passing a mixture of helium and hydrogen through an electric arc in the presence of sodium and titanium ions.
